TRAIN CONTROL SYSTEM FOR TOY
ELECTRIC RAILWAYSFrederick W. Hehre, Arlington, N. J., assignor to
Leon W. Rosenthal, New York, N. Y.

Application May 28, 1929, Serial No. 366,590

5 Claims. (Cl. 246—31)

This invention relates to train control systems for toy electric railways having a spur, crossover, loop or other form of track shunt employing one or more track switches.

5. An object of this invention is to provide means operative to prevent the derailment of a train by a track switch when the latter is prohibitive, that is when it will not permit the wheels of the train to continue uninterruptedly thereover; 10. preferably by means operatively synchronized with the track switch to deprive the train of propelling current at a place adjacent to or remote from said track switch to cause the train to tend to come to a stop before reaching said 15. switch; said deprivation of current being carried out preferably by electrically disconnecting or deenergizing an insulated track section at such place. Combined with these means tending to prevent derailment, my invention may also provide means, also preferably synchronized with the track switch, to supply the train with propelling current throughout the insulated track section to continue the movement of the train over said track switch, whether along the main 20. track in one direction or the other or into the shunt therefrom or into the main track from the shunt, when the track switch is permissive, that is when it will permit the wheels of the train to continue uninterruptedly thereover.
25. Other objects of the invention will appear as the description proceeds.

The accompanying drawing illustrates an application of my invention in which,

30. The figure is a circuit and schematic diagram disclosing the preferred embodiment in application to a crossover wherein the train is caused to come to a stop at a point remote from the prohibitive switch.

35. Referring particularly to the figure, there is shown two main track sections MT—1, and MT—2 respectively. A crossover CO joins these main track sections, and at the points where the crossover merges with the main tracks, the independently operable track switches TS—1 and TS—2 are positioned. Each switch is associated with an independent train control mechanism TC—1 and TC—2 respectively. The main tracks have rails 1, 1 and a center rail 2 having insulated sections 4 and 4², each separately connected or disconnected through their associated train control mechanism. The crossover track CO, has rails 1, and a power rail comprising two insulated sections 3 and 3², each adapted to be energized or deenergized through the above mentioned train control mechanisms.

The train control mechanisms TC—1 and TC—2 each comprise a reciprocating rod 10 operatively connected to the movable rail points of a track switch in the well known manner, and each carries a bridge member 20 of an electrical switch. This bridge member comprises an insulated bar having roller contacts mounted thereon, which contacts are connected to the positive side 103 of a power line. The bridge assembly is transversely mounted on a reciprocating rod 10. One contact roller of each bridge member 20 is arranged to engage the contacts 5 and 6 which are individually connected by wires 101 and 102 to insulated rail sections 3 and 4, and in the case of the other switch TC—2, to sections 3² and 4². Main track MT—1 is provided with an insulated track section 51, and the other main track MT—2 is provided with the corresponding section 52. The train controller TC—1 has contacts 12' and 12'' which engage the remaining contact roller of the bridge member 20, and likewise the train controller TC—2. Contact 12' of TC—1 is connected by a common wire 53 to insulated track section 51 and to contact 12'' of TC—2. Contact 12'' of TC—1 is connected by common wire 54 to contact 12' of TC—2 and to insulated section 52.

Instead of deenergizing an insulated track section adjacent a track switch, I may so interconnect my train control mechanisms as to deenergize an insulated track section remote from said track switch, as shown. It should be made clear here that in some toy electric railways the track shunts may be quite short, and it may not avail to stop a train on an insulated track section of the shunt by deenergizing said section,

30. because the coasting distance of the train may be longer than the insulated track section of the shunt. Of course, if the train is traveling at slow speed then the train may come to a stop 35. on the insulated section before striking the prohibitive track switch.

40. But, by the use of my system, I can assure that said train shall come to a stop, without the introduction of mechanical means, by providing 45. an insulated track section in the main track opposite that having the prohibitive track switch. Since in toy electric railways the main track is usually quite extensive, as large a section thereof may be deenergized as is necessary to 50. assure that the train, traveling at its greatest speed, will come to a stop thereon. Thus I provide an insulated track section 51 in main track MT1 and 52 in MT2. When the track switches are positioned as shown, section 51 is deener- 55.

gized so that a train coming from the left of MT1 will come to a stop on said section, instead of continuing into the crossover with the possibility of being derailed by track switch TS2 should it not succeed in coming to a stop on section 3².

It will be seen that only one of the sections 51 or 52 is electrically deenergized when the track switches are in opposite positions, the one energized being that with respect to which the track switch is permissive for the train to continue along the main track. In said figure, track switch TS2 being permissive with respect to a train coming from the right of MT2 for it to continue along said track, past said track switch, section 52 is energized, as is also, of course, 4², but said track switch TS2 being prohibitive to the crossover, section 51 is deenergized; and vice versa when the position of the track switches are reversed.

In conjunction with said train control system, I may employ a stationary signal light system which will indicate to an approaching train the positions of the track switches. Thus I connect lamps 82 and 83 in parallel with the circuits of sections 4 and 3 respectively, each lamp being adapted to light when the associated section is electrically connected. Preferably, the lamps are mounted near the switch in a signal box having the conformation of a five-sided right prism divided into two vertical compartments 84 and 85 by a horizontal partition. Lamp 82 is mounted in the upper compartment and lamp 83 in the lower compartment. Each compartment is provided with three windows or lenses of predetermined color and are so placed that one window in each compartment faces an approaching train on the spur or crossover, one window in each compartment faces a train on the main track approaching from the left, and one window in each compartment faces a train on the main track approaching from the right; in other words, a set of two windows, one above the other, faces each approaching train, one window of each set of superposed windows or lenses being lit and visible from the appropriate direction. As explained, either lamp 82 or 83 is lighted, because either section 4 or 3 is electrically connected, and thus either the top compartment or lower compartment will be illuminated.

The top compartment is provided with a red lens or window 90 facing a train approaching on the crossover; a green window 91 facing a train on the main track approaching from the left, and a green window 92 facing a train on the main track approaching from the right. Thus when the track switch TS1 is prohibitive to a shunt train, section 4 is electrically connected, and the upper compartment will be illuminated to disclose to a train on the crossover approaching the track switch, by a red signal, that said track switch is so prohibitive, and to trains on MT1 coming from the right or left that it is safe to continue past the track switch by a green signal. On the other hand when the switch is permissive with respect to the shunt, section 3 of CO is electrically connected and 4 disconnected, and the lower compartment is illuminated and the upper extinguished.

The said lower compartment is provided with a yellow lens or window 93 facing a train on the crossover approaching the track switch TS1, a red window 94 facing a train on the main track coming from the right and a yellow window 95

facing a train on the main track coming from the left. Thus when the lower compartment is illuminated, there is indicated, by a yellow signal, to a train on the crossover approaching the track switch TS1 to proceed with caution. The red lens 94, visible to a train on MT1 approaching from the right, is a signal to said train that the track switch TS1 is prohibitive to it and then the yellow lens 95, visible to a train on MT1 approaching from the left, indicates that the train should proceed with caution over section 51. If desired, additional signal lights electrically connected in series or parallel to 82 and 83 might be placed at some remote place, as for instance at a signal tower, to indicate at that place the position of the switch.

It is obvious that a similar signal system might be employed for a similar purpose in conjunction with the train control TC2 operated by or with track switch TS2.

It is obvious also that the rod 10 of the train control mechanism of any of the embodiments may be operated manually, or electromagnetically from a switch tower, or in any other suitable way, and that rotatable signals, semaphores, gates or other devices may be directly or indirectly operated synchronously with the track switches to simulate standard railroad practice.

Having described my invention, what I claim is:

1. In a toy electric railway, two main track sections, a shunt track connecting the same, track switches at the junctures of said shunt track and main track sections, and means operative when said switches are in opposite operative positions to de-energize an insulated section in front of the switch which is permissive for a train to enter the shunt track.

2. In a toy electric railway, two main track sections, a shunt track connecting the same, track switches at the junctures of said shunt track and main track sections, and means operative when the switches are in opposite operative positions to de-energize an insulated section in front of the switch which is permissive for a train to enter the shunt track, as well as to de-energize an insulated section in said shunt track.

3. In a toy electric railway, two main track sections, a shunt track connecting the same, track switches at the junctures of said shunt track and main track sections, and means operative with one of said switches to de-energize an insulated section in the opposite main track adjacent the other switch of the shunt track.

4. In a toy electric railway, two main track sections, a shunt track connecting the same, track switches at the junctures of said shunt track and main track sections, means operative with one switch to control an insulated section between said switches, and means associated with the first-named means for then controlling an insulated section of the main track adjacent the remaining switch.

5. In a toy electric railway, two main track sections, a shunt track connecting the same, manually controlled track switches at the junctures of said shunt track and main track sections, means operative with one of said switches to control an insulated section between the switches, and means associated with the first-named means for then controlling a section of the main track adjacent the other switch.
